UNITED STATES PATENT OFFICE.

PIERRE DANSEREAU, OF MONTREAL, QUEBEC, CANADA.

CARRIAGE-TOP.

SPECIFICATION forming part of Letters Patent No. 251,704, dated January 3, 1882.

Application filed November 5, 1881. (No model.)

To all whom it may concern:

Be it known that I, PIERRE DANSEREAU, of the city and district of Montreal, Province of Quebec, Canada, have invented certain new and useful Improvements in Vehicles; and I do hereby declare that the following is a full, clear, and exact description of the same.

This invention has reference to the construction and arrangement of a vehicle-top adapted to be applied to any class of vehicle requiring a top, and including a buggy, wagon, carriage, sledge, &c., and it can therefore be used with vehicles having one or more seats.

I have already obtained Letters Patent of the United States, granted me on the 5th July, A. D. 1881, under No. 243,860, and of Canada, granted me on the 7th May, A. D. 1881, under No. 12,739, for an "improvement in carriages," in which the top is made in two principal parts which close up, one principal part arranged to close and turn forward, the other principal part to close and turn backward. By my present invention the whole top turns backward. In my said patented invention eight posts are required, as shown, to hold up the top. In my present invention only two are necessary. Nevertheless four may be used, if desired, in some cases. For these and other reasons, which will be understood by the following specification, it will be seen that the present invention gives a much cheaper form of top than those at present in use, and one more applicable to all classes of vehicles.

In the drawings hereunto annexed similar letters of reference indicate like parts, and Figure 1 is a side elevation of the application of my invention to a buggy. Figs. 2 and 3 are modifications of the manner of dividing and closing the top shown in Fig. 1. Fig. 4 is a side elevation of the application of the invention to all classes of vehicles having more than one seat. Fig. 5 shows the manner of closing the top shown in Fig. 4. Fig. 6 is a modification of the top shown in Fig. 4. Fig. 7 is another modification of dividing the top. Fig. 8 shows the manner of closing and turning back the top in Fig. 7.

I will now first refer to Figs. 1, 2, and 3, which is the form for a buggy or one-seated vehicle, and afterward refer to the application to other vehicles.

Letter A is any ordinary body or seat, to which is attached, by a hinge, B, a post, C. On this is secured, as shown, a part of a top, D, having two sub-portions, E and F, as shown in Fig. 1, hinged, as shown at G and H, thereto, catches or fastenings of the ordinary kind for such purposes being provided for securing the parts E F in the relative positions shown in both dotted and full lines. In these catches and fastenings I do not claim any invention. Therefore I shall not describe them.

Regarding the top formed of the parts D, E, and F, it is constructed of a light wood or other frame with material stretched tightly over it. Said material may be water-proof fabric, thin wood, or sheet metal, &c., the object being to have a top in its parts rigid, so that the said parts or divisions do not fold up or bend in themselves—such as the leather, &c., tops with bows at present in use—because such tops soon become shabby from the folds and ribs formed by the bows, and these cannot be cured except by putting on a new covering, whereas by my rigid top, whenever it becomes shabby, paint and varnish will give it a perfectly new appearance, thus saving much expense in keeping the vehicle in a handsome and good condition.

I is an ordinary carriage-joint, and K the back curtain. In these no novelty exists.

In Figs. 2 and 3 the top is divided into two parts instead of three. Otherwise they will be constructed and arranged with the buggy in the manner above described for Fig. 1.

We now come to Figs. 4, 5, and 6. In Fig. 4 an outline of a three-seated vehicle is shown. Here the top is divided into the parts or divisions D, E, and F. It is provided with the same posts C, hinged to B, as shown in Fig. 1. Joints I will also be provided. The manner of closing up this cover is shown in Fig. 5, and it is then turned down in the same way as the top in Fig. 1. It will be remarked that a long hinge, G, is used in this case to enable the part E to come to the position shown with the part F.

K is the back curtain; A', the back seat; B', the front seat, and C' the driver's seat. D' is the front curtain, from which it will be seen that the driver is left out in the cold, &c., in the usual way.

To strengthen the junction of the post C with D, I should prefer to insert a strong angle-plate or knee, as shown by dotted lines at E'.

- 5 By dotted lines I have indicated that, if desired, a second pair of posts, H', may be added in front of the doorway for further firmness and support. These posts H' will be made of such length that they are equal to the distance 10 from 1 to 2, (see Fig. 4,) and will be hinged to a distance-piece, H², secured to the seat B', which makes up the whole distance from B' to F, so that when turned down, as also indicated, they just reach, or nearly reach, the 15 front curtain. The junction of the posts H' with F will be formed with dowel-pins, and I should prefer to add a removable T-plate to cramp the three parts D, F, and H' firmly together, which may be done by screw-bolts 20 passing through it and the framing and posts, or in any ordinary manner in use in such cases. I' are rests for the posts H' to turn down to, so that when in that position they form arms to the seat B'.
 25 It will be seen that in my present invention none of the turn-down parts extend beyond the front seat, B'. Therefore no neck or space is required between the seat B' and the driver's seat C'.
 30 If the vehicle is to have only two seats, the seat B' will be the driver's seat, and the curtain D' will be dispensed with or removed back behind the seat B'.
 The above description of Figs. 4 and 5 also 35 applies to Fig. 6, the only difference being in the closing of the parts D, E, and F, and the manner shown is exactly like that in Fig. 1. In some cases to close the top in three parts, one beside the other, as in Fig. 5, may render 40 it too thick to find space to turn down the posts

C and clear the back of the back seat without making the posts C and posts H', if used, too long.

Side curtains may be provided, or, if desired, removable glass sashes, which may be 45 put in place and secured when the posts are up and removed and put under one of the seats, &c., when they are down.

I will now describe the modification shown in Figs. 7 and 8, where the top is divided into 50 the same three parts, D, E, and F, with two more parts, A² B², added. The part D has the posts C attached to it, as described for the other figures.

In Fig. 7 the posts H' are shown with two 55 hinges, H³, so that they will double up and turn down, as indicated by the dotted lines at H'. The seats A' B' C' are the same relative seats described in Fig. 4.

Now, in the foregoing description the top 60 has been described as divided into two, three, and five parts, and from this any man of ordinary skill in the business will at once see that it may be divided into four parts. Therefore I do not think it necessary to describe 65 such a division.

What I claim, and wish to secure by Letters Patent, is as follows:

The combination of a vehicle-top divided into rigid parts, all of which said parts are hinged 70 together, and one of said parts being attached fixedly to the single pair of posts C, with the said posts C hinged to the body of the vehicle, and arranged to carry the whole of the top and turn back therewith, substantially as described. 75

PIERRE DANSEREAU.
